UNITED STATES PATENT OFFICE.

RICHARD A. LOCKARD, OF BERWICK, PENNSYLVANIA, ASSIGNOR TO AMERICAN CAR AND FOUNDRY COMPANY, OF NEW YORK, N. Y., A CORPORATION OF NEW JERSEY.

DRAWBAR AND BUMPER.

Application filed May 3, 1922. Serial No. 558,064.

To all whom it may concern:

Be it known that I, RICHARD A. LOCKARD, residing at Berwick, Columbia County, State of Pennsylvania, and being a citizen of the 5 United States, have invented certain new and useful Improvements in a Drawbar and Bumper, of which the following is a full, clear, and exact description, such as will enable others skilled in the art to which it 10 appertains to make and to use the same, reference being had to the accompanying drawings, which illustrate the preferred form of the invention, though it is to be understood that the invention is not limited to 15 the exact details of construction shown and described, as it is obvious that various modifications thereof within the scope of the claims will occur to persons skilled in the art.

20 In said drawings:

Fig. 1 is a plan view of my improved drawbar end and bumper shown applied to one end of a mine car floor;

Fig. 2 is a central vertical section taken 25 on the line 2—2 of Fig. 1;

Fig. 3 is a view part in elevation and part in section taken on the line 3—3 of Fig. 1;

Fig. 4 is a view similar to Fig. 1 of a modified form of my device;

30 Fig. 5 is a central vertical section taken on the line 5—5 of Fig. 4; and

Fig. 6 is a view part in elevation and part in section taken on the line 6—6 of Fig. 4.

It is an object of my invention to provide 35 an improved drawbar end and bumper for mine cars which will be of simple and rugged construction and which can be readily applied to new cars or substituted for constructions now in use.

40 It is also an object of my invention to provide a drawbar end and bumper of such construction that buffing stresses will be distributed so that the stresses will be resisted by the floor as a whole thus obviating the 45 necessity of providing a special center sill and relieving the center portion of the car floor of excessive stresses.

With these and other objects in view my 50 invention comprises a car floor 1 formed of a plurality of longitudinally extending boards 2 of suitable thickness. To the center board 2 there is secured, in any desired manner, a drawbar 3 which extends, substantially, the length of the car and is connected, at its ends, by bolts or rivets 4 to a

strap-like portion 5 of a drawbar end and bumper member 6.

As shown in Figs. 1, 2 and 3, the drawbar end and bumper member 6 is formed as an integral casting comprising the strap portion 5, a clevis portion 7 and a tapering plate portion 8 which serves as the upper flange of a channel-shaped portion having a web 9, which serves as a buffing face, and a lower flange 10, the upper and lower flanges 8 and 10 being spaced apart sufficiently to receive the ends of the boards 2 and a filler block 11. Reinforcing ribs 12 connect the strap portion 5 and clevis portion 7 and webs 13 connect the clevis portion 7 and plate 8 portion 8. The channel-shaped portion is shaped to conform to the floor end and is of such extent as to embrace the greater part of the floor end so that the buffing stresses will be distributed to all the boards comprising the car floor. The channel-shaped portion is secured to the floor by the bolts 14 which pass through openings in the boards 2, filler block 11, and the upper and lower flanges 8 and 10. Alined openings are formed in the clevis portion 7, upper and lower flanges 8 and 10, center board 2 and filler block 11 to receive a coupling pin (not shown).

In the modification shown in Figs. 4, 5 and 6, part of the upper flange 8 is omitted and the drawbar 3' extends from end to end of the car, engaging with web portion 9 at each end of the car. In this construction the end of the drawbar 3' lies directly under the clevis portion 7 and is provided with an opening aligning with the opening in the clevis portion 7 to receive a coupling pin thus providing for the direct transmission from the coupling pin to the drawbar 3' of a part of the draft stresses.

What I claim is:

1. The combination of a car floor comprising boards extending longitudinally from end to end of the car, channel-shaped buffer means having a tapered upper flange embracing the ends of a plurality of said boards, draft means spaced from said buffer means and formed integral with said buffer means and a drawbar connected to said means.

2. The combination with a car floor, of a buffer means adapted to distribute the buffing stresses in said car floor comprising a channel-shaped buffing portion embracing

the end of said floor, a tapered securing portion formed therewith and a draft member formed integral with said buffing and securing portions.

5. The combination of a car floor comprising a plurality of longitudinal members, of a buffer means adapted to distribute the buffing stresses in said car floor comprising a channel-shaped portion adapted to ²⁵ brace the ends of a plurality of said members, a plate-like portion extending from the upper flange of said channel-shaped portion, draft means secured to said plate-like portion and spaced therefrom and means for ³⁰ connecting said draft means to a drawbar.

4. A buffer means for cars comprising a casting having a curved buffing portion having inwardly turned flanges, the upper flange being extended into a plate portion, a draft ²⁰ member projecting from said plate portion,

and reinforcing walls connecting said plate portion and draft member.

5. The combination of a car floor composed of boards extending longitudinally of the car and a buffer means comprising ²⁵ a casting having a channel-shaped portion embracing the ends of a plurality of said boards, a plate portion extending from the upper flange of said channel-shaped portion, a draft member projecting upwardly ³⁰ from said plate portion and reinforcing walls connecting said draft member and said plate portion.

In witness whereof I have hereunto set my hand in the presence of two witnesses.

RICHARD A. LOCKARD.

Witnesses:

I. L. B. MARTZ,
W. E. BITTINBINDER.
